UNITED STATES PATENT OFFICE.

WALTER R. SCHLAGE, OF SAN FRANCISCO, CALIFORNIA.

COMBINATION MARKER GAUGE.

Application filed October 24, 1925. Serial No. 64,489.

This invention relates to a combination marker and gauge.

The object of the present invention is to generally improve and simplify the construction and operation of the devices of the character described and to provide a combination marker and gauge whereby drilled or bored holes requiring a predetermined position with relation to each other may be accurately marked before drilling; to provide a gauge whereby the hole may be gauged or measured during or after the completion of the drilling operation and, furthermore, to provide a gauge whereby the drilling or boring tool, for instance, an expansion bit, may be adjusted or properly set before the drilling operation.

One form which the invention may assume is exemplified in the accompanying specifications and drawing in which—

Figure 1 is a perspective view of a portion of the door showing the door bored and ready for the reception of the door lock,

Figure 2 is a perspective view of the combination marker and gauge,

Figure 3 is a cross section of a portion of a door showing the large hole partially bored and the head of the plate inserted to determine if the bit is cutting to proper size.

When fitting a certain type of lock to doors, it is only necessary to bore two holes with an ordinary brace and extension bit. One hole is bored completely through the door from face to face and is fairly large in diameter as it receives the lock housing which carries the spindles and door knobs. The other hole is fairly small in diameter as it merely carries a lock housing and latch. It is bored in the edge of the door at right angles to the first hole and intersects the same. The boring of the holes is, of course, a very simple and quick operation and as the holes must assume an accurate and predetermined position with relation to each other in order that the latch mechanism may be properly connected to the main lock, it is evident that considerable care must be taken in measuring, laying-off and marking the holes before boring the same and care must also be taken that the expansion bit is properly adjusted as a slightly undersized hole will prevent insertion of the lock mechanism and latch, while an oversized hole will cause undue play and a poor fit.

The combination marker and gauge form-

ing the subject matter of the present application eliminates these troubles as it first of all permits the work to be accurately and quickly laid off and marked. Secondly, it permits accurate adjustment of the extension bit, and, third, permits measuring or gauging of the holes during or after completion of the boring operation.

The combination marker and gauge is preferably constructed of thin sheet metal which may be blanked out and formed by means of dies. The plate consists of a rounded or circular head member "A"; a reduced extension "B" and a foot member "C". The head member "A" is centrally perforated as at 2 to form a marker opening and the foot member is notched as at 3 to form a second marker opening.

It may furthermore be stated that the foot member is bent at right angles to the main plate section consisting of the members "A" and "B", this being necessary as the holes to be marked are disposed at right angles with relation to each other.

In actual operation "D" indicates a portion of a door and "E" and "F" the holes drilled or bored therein. The hole "E" extends through the door from face to face and is fairly large in diameter, as previously stated, as it receives the main lock mechanism. The hole "F" is fairly small in diameter and is drilled through the edge of the door to a point where it intersects the main hole "E".

When the carpenter, or other mechanic, who is fitting the locks to the doors, desires to lay off and mark the holes prior to boring same, he merely applies the combination marker and gauge to the door in the position indicated by the dotted lines in Figure 1. By inserting a pencil or like implement in the perforation 2, he marks the center of the large hole to be bored and by inserting the pencil in the V notch he determines the position of the smaller hole "F"; that is, he places a square on the edge of the door and draws a line through the V notch pencil mark, as indicated at 4, and then determines a central point on this line which is then marked for the drilling of the small hole. If he employs an extension bit, he places the center of the bit in the perforation 2 of the plate and then adjusts the extension bit until the cutting edge aligns with the outer periphery of the circular member "A". With the bit adjusted, it is only necessary to drill

the large opening "E". In drilling the first opening, it is advisable to remove the bit before the hole is completed so that the member "A" of the plate may be inserted as shown in Figure 3. The head thus serves as a gauge and it is therefore easy to determine whether the hole cut by the extension bit is snug or large. If the adjustment proves accurate, it is only necessary to complete the 10 hole and to bore as many other doors as may be desired. After all of the large holes have been drilled, he can readjust the expansion bit to the small hole "F" or install a standard bit if desired. The plate serves 15 the function of a gauge and also serves the function of laying out and marking the door. This simplifies the work for the mechanic, reduces the time required and insures more accurate and uniform measurements. 20 While certain features of the present invention are more or less specifically de-

scribed and illustrated, I wish it understood that changes and variations may be resorted to within the scope of the appended claims.

Having thus described my invention, what 25 I claim and desire to secure by Letters Patent is—

1. A combination marker and gauge comprising a plate having a foot extension at one end thereof and bent at right angles to 30 the plate; said plate and foot extension having marker openings formed therein and a gauging head formed on the plate.

2. A combination marker and gauge comprising a plate, having a rounded head member 35 on one end and a foot extension bent at right angles thereto on the opposite end; said rounded head member having a marker opening formed centrally thereof and said foot extension having a marker notch formed 40 in one edge.
